INVENTOR
Edward Ellis,

BY
G. C. Kennedy.
ATTORNEY

UNITED STATES PATENT OFFICE.

EDWARD ELLIS, OF IOWA FALLS, IOWA.

SHOE-FASTENER.

No. 889,301.

Specification of Letters Patent.

Patented June 2, 1908.

Application filed August 30, 1906. Serial No. 332,650.

To all whom it may concern:

Be it known that I, EDWARD ELLIS, a citizen of the United States of America, and a resident of Iowa Falls, Hardin county, Iowa, 5 have invented certain new and useful Improvements in Shoe-Fasteners, of which the following is a specification.

My invention relates to shoe fasteners, and the object of my invention is to provide an 10 inexpensive and easily manipulated fastener for shoe-strings, which may be easily attached to or removed from a shoe. This object I have accomplished by the means which are hereinafter described and claimed, and 15 which are illustrated in the accompanying drawings, in which—

Figure 1 is a side elevation of my improved shoe-string fastener as attached to a portion of the upper leather of a shoe, Fig. 2 is a plan 20 view of the fastener and its clutch-plate, Fig. 3 is a detail view of the clutch-plate and the screw, Fig. 4 is a detail view of the coil spring and its clip in perspective, and Fig. 5 is a detail view of the screw showing it with its head 25 flattened and extended to take the place of a clutch-plate, while Fig. 6 is a view of my improved fastener as actually used upon a shoe to fasten thereto the ends of a shoe-string.

Similar letters refer to similar parts 30 throughout the several views.

My improved fastener consists essentially of four parts or coöperating elements, and as will be afterwards shown, one of these elements may be so changed as to obviate the 35 use of one of the other elements.

I have shown a screw *a* having a thin flattened head *b*, said head providing a seat for a contact or clutch-plate *c* formed of a thin metal plate perforated that the screw *a* may 40 pass therethrough. One side of said contact or clutch-plate *c* is lengthened to furnish a bearing for the clip *e* of the coil-spring *d*, the coils of the latter encircling the screw *a* above the said clutch plate, the upper leather *h*, 45 however, being inserted between them. A nut *f* fits upon the screw *a* and compresses the coils of the spring *d* upon the upper leather *h*, as shown in Fig. 1.

In use, the fastener may be connected to 50 the upper leather, by perforating the latter, and passing the screw *a* through such perforation, keeping both the screw head and the clutch-plate *c* on the same side of the leather and on the inner side of the shoe. The 55 spring *d* is then slipped over the screw so as

to permit the clip *e* to bear against the leather *h* just over the lengthened portion of the contact or clutch-plate *c*, when the nut may be screwed down to effect proper compression of the spring. As shown in Fig. 1, the tip of 60 the clip *e* is slightly raised to permit ease in drawing a shoe-string *m* thereunder. To fasten the shoe-string after it has been laced, one end *i* of such string is first encircled about the stud above the clip *e*, then drawn 65 under said clip, the latter by its tension against the string and clutch-plate, holding the end of such string securely. The other end *l* of the string having been secured between the shoe and the end *i* as shown, may 70 be prevented from slipping out by simply knotting it just above the end *i*.

In Fig. 5 I have shown an alternative form of screw *a* having a flattened and extended head, whose extension *b* serves to take the 75 place of the clutch-plate *c*.

Having described my invention, what I claim as new, and desire to secure by Letters Patent, is—

1. A shoe fastener, comprising a contact- 80 plate on the inside of the shoe-top having a threaded shank projected therefrom, such shank being located near one end of said contact-plate and adapted to pass through the material of the shoe, a coil-spring about said 85 shank bearing upon such material and over said contact-plate and having a laterally extending uplifted end adapted to bear upon such material over the extension of said contact-plate, said coil-spring removably se- 90 cured to said shank.

2. A shoe fastener, comprising a flat-headed threaded stud, a contact-plate seated about said stud inside of the shoe-top and having an extension at one side, said stud 95 adapted to pass through the material of the shoe-top and said contact-plate to contact with the inner surface of the said material, a coil-spring about said stud adapted to bear against the outside of said material over said extension, and means for adjustably compressing said spring upon said material and contact-plate and for securing it about said stud.

Signed at Waterloo, Iowa, this 11th day 105 of Aug. 1906.

EDWARD ELLIS.
